Primary Examiner — Shawn T Gingrich*(74) Attorney, Agent, or Firm* — Banner & Witcoff, Ltd.(57) **CLAIM**

The ornamental design for a connector, as shown and described.

DESCRIPTION

FIG. 1 is a front top perspective view of a connector showing our new design;

FIG. 2 is a front bottom perspective view thereof;

FIG. 3 is a rear bottom perspective view thereof;

FIG. 4 is a front view thereof;

FIG. 5 is a rear view thereof;

FIG. 6 is a top view thereof;

FIG. 7 is a bottom view thereof;

FIG. 8 is a left side view thereof; and,

FIG. 9 is a right side view thereof.

The uneven-length broken lines immediately adjacent to and surrounding the shaded area define the peripheral bounds of the claimed design. The even-length broken lines depicting the remainder of the connector form no part of the claimed design.
